J. T. ANTHONY.
LOCOMOTIVE BOILER FIRE BOX.
APPLICATION FILED OCT. 1, 1913.

1,118,615.

Patented Nov. 24, 1914.

UNITED STATES PATENT OFFICE.

JAMES T. ANTHONY, OF EAST ORANGE, NEW JERSEY, ASSIGNOR TO AMERICAN ARCH COMPANY, OF NEW YORK, N. Y., A CORPORATION OF NEW YORK.

LOCOMOTIVE-BOILER FIRE-BOX.

1,118,615.

Specification of Letters Patent. Patented Nov. 24, 1914.

Application filed October 1, 1913. Serial No. 792,807.

To all whom it may concern:

Be it known that I, JAMES T. ANTHONY, a citizen of the United States, and a resident of East Orange, New Jersey, have invented 5 certain new and useful Improvements in Locomotive-Boiler Fire-Boxes, of which the following is a specification.

My invention relates to improvements in locomotives and has particular reference to 10 improvements in locomotive boiler fire boxes.

The object of my invention is to provide a locomotive boiler furnace of the extension combustion chamber type, which shall prevent 15 the free escape of gases of combustion from the fire-box; which shall prevent the escape from the fire-box of cinders and other unburned fuel particles which are carried by the gases of combustion, and which shall be 20 provided with simple means for the withdrawal and removal of the accumulated cinders from the extension of the fire-box.

A further object of my invention is to provide a construction for locomotive boiler 25 furnaces of the extension combustion chamber type which shall effectively prevent the ejection of cinders and other unburned particles from the locomotive boiler stack and provided with means passing through the 30 boiler below the extension for the removal of the accumulated cinders.

A further object of my invention is to provide a cinder outlet for such fire-boxes which, once installed, shall be substantially 35 permanent; which shall be so constructed that it will not act as a stay to prevent necessary relative movement of the boiler sheets connected therewith.

A further object of my invention is to 40 provide a thimble, for connecting two opposed sheets, of such form or construction that the connected sheets shall be free to assume their positions as defined by the changing temperatures or pressure in the boiler 45 without unduly straining the thimble; and which shall be capable of lengthening or shortening longitudinally to a certain extent without producing rupturing strains therein.

My invention consists in a locomotive 50 boiler of the extension combustion-chamber type provided with a transverse refractory wall partly closing the mouth of the extension and adapted to cause the deposit of the cinders between the wall and flue sheet, a 55 thimble passing through the water space

below the extension secured at its end to the adjacent sheets of the boiler and provided with circumferential corrugations between its ends adapted to permit the thimble to accommodate itself to the changing relative positions of the boiler sheets without producing undue strains within the thimble itself.

My invention also consists in a locomotive boiler having a water space defined by opposed boiler sheets, a thimble projecting through this water space and connected at its ends to the confining sheets and adapted to provide a passageway from the interior of the boiler to the exterior thereof, the ends of the thimble being rigidly secured, pressure and steam tight, to the sheets of the boiler and the intermediate portion of the thimble, being provided with bellows like corrugations which permit the thimble to 70 lengthen and shorten in accordance with any variation in relative positions of the two boiler sheets without causing a rupture of the thimble.

My invention also consists in the several 80 arrangements and combinations of parts and in the features of construction whereby the above and other objects are attained and all as hereinafter described and particularly pointed out in the appended claims. My invention will be more readily understood by 85 reference to the accompanying drawings forming a part of this specification and in which;

Figure 1 is a central vertical longitudinal 90 section of a locomotive fire-box of the extension-combustion chamber type provided with a refractory cross wall and embodying my invention; Fig. 2 is a transverse section of the fire-box on the line 2—2 of Fig. 1; 95 Fig. 3 is a detail section of the lower part of the extension of the fire-box illustrating a modification of my invention; and Fig. 4 is a view similar to Fig. 3 showing another modified form of my invention.

One of the functions of a cross wall in a locomotive fire-box is to prevent the gases of combustion from flowing directly from the fuel bed to the flues and cause them to linger in the fire-box and to pass over the 105 interior surface thereof to the end that substantially complete combustion may take place before the gases escape through the flues and further to permit and to cause the gases to effectively give up their heat to the 110

water in the boiler. A further result of the installation of such walls is that they serve or tend to cause the gases of combustion to deposit their burden of cinders or unburned fuel particles before the gases enter the flues and in the space between the wall and flue sheets. Boilers of this type as constructed have a water space below the extension of the fire-box and the problem of providing a cinder outlet to permit the removal of the cinders from the extension space has been a difficult one to solve for the reason that when it has been attempted to provide openings through which the cinders could be removed the changing dimensions of the boiler, due to variations in temperature and pressure, has been such that the tubes or thimbles have been quickly fractured and destroyed, thus causing expensive delays in the operation of the locomotive and expensive repairs. By means of my invention I am enabled to overcome these objectionable features and provide a cinder outlet for this type of boiler which, once stalled, is permanent in that the walls of the thimble are so constructed that they can accommodate themselves to any ordinary or unusual changes of dimensions of the boiler which may be due to changes of temperature and pressure, without being unduly strained.

A locomotive boiler A as illustrated in the drawings consists of a main combustion chamber a^1 of the usual form provided at its forward end with a substantially cylindrical fire box extension which projects forwardly into the barrel of the boiler from the forward end of the main combustion chamber. This fire box as illustrated consists of a flue sheet a^3 at the forward end of the auxiliary combustion chamber, a rear sheet a^4 at the rear end of the main combustion chamber, a crown sheet a^5 which extends from the rear sheet to the flue sheet, a floor sheet a^6 which connects the flue sheet with the front water leg a^7 arranged at the forward end of the grate space a^8 and side sheets a^{98} . The rear end of the fire-box is provided with a fuel door or opening a^9 and flues a^{10} lead forwardly into the boiler from the flue sheet. The floor a^6 of the extension of the fire-box is spaced from the outer sheet a^{11} of the boiler providing a water space a^{12} between these two sheets and which is connected at its rear end to the water leg a^7 . This space forms a part of the water space of the boiler and is in free communication therewith. These sheets a^6 and a^{11} are substantially parallel throughout the lower part of the fire-box extension and are held in spaced relation by means of stay-bolts a^{18} , but it should be understood that notwithstanding a sufficient number of stay-bolts are made use of between the two sheets as defined by the best boiler practice the two

sheets are not rigidly related to each other for the reason that the boiler as a whole is more or less flexible and is subject to slight changes of shape and dimensions due to the extreme pressures and temperatures which are made use of in modern locomotive practice. 70

In order to prevent the direct flow of the gases of combustion from the fuel bed to the flues and cause them to flow over the interior surface of the fire-box, I provide a refractory cross wall B arranged in the rear end of the mouth of the fire-box extension a^2 and rising substantially half of the height of the fire box at this point, and I also provide as an additional means of preventing the direct flow of the gases and for the purposes of causing these gases to be thoroughly intermingled and intermixed a rearwardly extending projection b^1 upon the upper end of wall B which extends over the forward end of the gate and causing the rising fire box gases to be whirled and mixed before they enter the extension of the fire box. The space a^{14} above the wall which forms the connecting passage between the main combustion chamber a^1 and the auxiliary combustion chamber a^2 is of course of much smaller cross sectional area than either of the combustion chambers and consequently as the gases of combustion flow through this passage they are more or less compressed and as they enter the auxiliary combustion chamber they expand and their rate of flow is consequently greatly diminished. In consequence of this the gases which have been caused to lift cinders and unburned fuel particles from the bed of fuel and carry them upward into the fire-box, by reason of the strong artificial draft employed, are caused to deposit these cinders and unburned fuel particles in the extension of the combustion chamber and before the gases of combustion enter the flues. This deposit of the cinders and fuel particles is assisted by the rearward projection b^1 on the cross wall for the reason that this extension serves to cause the gases to be whirled over the wall and drawn into the combustion chamber in a direction best to throw the cinders and particles to the bottom of the combustion chamber where they remain until removed. 110

In order to be able to remove the cinders which accumulate in the lower part of the auxiliary combustion chamber I provide a cinder outlet C which passes through the water space a^{12} and permits access to the extension combustion chamber from the exterior of the boiler. I preferably make the cinder outlet in the form of a tube extending through the water space a^{12} and connected at its ends to the boiler sheets a^6 and a^{11} . For the purpose of conveniently connecting the tube to the boiler sheets I flange 125

the sheet a^6 inwardly and the sheet a^{11} outwardly, providing flanges a^{15} by means of which the ends of the tube can be conveniently riveted and secured to the boiler.

5 To permit the tube forming the cinder outlet to accommodate itself to changes of relative position of the sheets a^6 and a^{11} without producing undue strain in the tube, I provide the portion of the tube which lies

10 between the two boiler sheets with circumferential corrugations c^1 of what may be aptly described, bellows form, and which permit slight longitudinal extension or contraction of the tube without subjecting the

15 tube to undue or fracturing strains. In the form of cinder outlet shown in Figs. 1 and 2, the two ends of the tube are substantially of the same diameter and the corrugations are formed inwardly from the out-

20 side surface of the tube so that the tube can be readily entered through one of the boiler sheets to its position and thereafter tightly secured by riveting and calking. I provide the lower end of the tube C with a

25 removable cover c^2 which normally closes the outer end of the cinder outlet and prevents the entrance of air at this point.

For the purpose of causing the cinders and other particles to gravitate into the

30 tube C, I provide a hopper-shaped floor a^{16} in the extension of the combustion chamber which inclines in all directions toward the center or toward the inner end of the cinder outlet and the jarring and tremor produced

35 by the locomotive in its movement over the rails cause the particles to work downwardly into the cinder outlet.

In Fig. 3 I have shown a slight modification of my invention. In this form the

40 corrugations c^1 of the cinder outlet are smaller in diameter than the opening in the outer boiler sheet and the tube c^3 is tapered from end to end and is smaller at its lower end than at its upper end whereby it can be

45 entered into its position from the interior of the fire box and as the corrugations are smaller in diameter than the hole provided in the sheet a^6 they do not hinder the insertion of the tube c^3 into its position and fur-

50 thermore as they are arranged to extend outwardly from the interior surface of the tube they do not form shoulders which tend to support the cinders in the tube or prevent their easy removal therefrom. In Fig.

55 4 I have shown a form of cinder outlet which can be inserted into position from the exterior of the boiler. In this form of my cinder outlet I taper the tube c^3 from end to end similar to the form shown in

60 Fig. 3 except that the small end is at the top and the corrugations c^1 , which I form in this tube, extend both internally and ex-

ternally and are thus most easily formed, for these corrugations require the least amount of disturbance or change of form 65 of the material of the tube. The corrugations c^1 are smaller in diameter than the opening provided in the sheet a^{11} and consequently, although they extend outwardly beyond the immediate contiguous surface 70 of the tube, they do not hinder the insertion of the tube to its position. In each case the outlet is provided with a cover-plate c^2 which normally closes the lower end of the tube and prevents the entrance of air. 75

It will now be clear that by these means I am enabled to provide a locomotive boiler fire-box of the extension combustion chamber type with a cinder outlet which can be readily installed and which when once installed is not subjected to fracture due to changing temperatures or pressures. Furthermore the application of my corrugated thimble which is adapted to connect two opposed boiler sheets is not limited to the 80 use of a cinder outlet, for it may form a cinder outlet or it may form a passage through a space in a boiler, which may be used for purposes other than the removal of cinders, and as many modifications of my 85 invention will readily suggest themselves to one skilled in the art, I do not limit or confine my invention to the specific structures herein shown and described. 90

I claim:

1. In a locomotive boiler of the extension fire-box type having a water space beneath the extension defined by the floor of the extension and the outer shell of the boiler, a tube extending through the water space 100 rigidly connected at its ends to the opposed boiler sheets, said tube being corrugated between its ends and one of the ends being larger in diameter than the largest diameter of the corrugations. 105

2. In a locomotive boiler of the extension fire-box type having a water space below the extension, a tube passing through said water space below the extension, and through which cinders accumulating in the 110 extension may be withdrawn, said tube having corrugations between its ends smaller in diameter than the opening through which the tube is entered the ends of the tube being connected rigidly with the adjacent 115 boiler sheets and a cover normally closing the lower end of said tube.

In testimony whereof, I have hereunto set my hand, this 22nd day of Sept., 1913, in the presence of two subscribing witnesses. 120

JAMES T. ANTHONY.
